LAGGING FOR REELS

Arthur A. Bureau, Chicago, Ill., assignor to Western Electric Company, Incorporated, New York, N. Y., a corporation of New York

Application December 13, 1938, Serial No. 245,377

18 Claims. (Cl. 206—59)

This invention relates to lagging for reels used for storing and transporting heavy material, such as lead covered cable, particularly to lagging provided with means whereby it may be secured upon such reels.

Objects of the present invention are the provision of an improved construction for reel lagging having a low weight consistent with the required structural strength and simple and practical securing means whereby it may be readily and effectively secured to reels and easily removed therefrom.

In accordance with the above objects, the invention in one embodiment thereof comprises a plurality of segmental shaped sheet metal lags for enclosing a metal reel which includes annular head rims upon which the lags are placed side by side. Each lag comprises a plurality of integral channel-like formations terminating in radially extending end arms, the formations having welded thereto reinforcing side walls extending from the outer peripheral channel walls inwardly toward the outer surfaces of inner walls interconnecting and extending from the side arms of the channel formations, the latter walls bearing upon the head rims. The lags are provided with means adjacent the inner edges of the head rims to prevent substantial longitudinal movement of the lags on the reel. Formed in the opposite side edges of each of the channel side arms and the end arms adjacent the outer surfaces of the interconnecting walls and the inner edges of the reinforcing side walls of the lags and a filler or sealing lag are slots for the reception of a retaining member which encircles the rims under tension for securing the lagging upon the reel. Means secured to each of the head rims at diametrically opposite points serves to effectively prevent the accidental displacement of the member out of the slots.

Other objects and advantages of this invention will more fully appear from the following detailed description, taken in connection with the accompanying drawings, in which:

Fig. 1 is a view in side elevation of a metal cable reel provided with the improved lagging and means for securing the lagging to the reel according to one embodiment of the invention;

Fig. 2 is a fragmentary vertical section taken on the line 2—2 of Fig. 4;

Fig. 3 is an enlarged detail view of the right end of Fig. 2;

Fig. 4 is an enlarged fragmentary side view of Fig. 1;

Fig. 5 is an enlarged fragmentary detail verti-

cal section taken on the line 5—5 of Fig. 4 at a point intermediate the reel heads illustrating U-shaped reinforcing members provided at opposite ends of the lags;

Fig. 6 is a fragmentary plan view of the filler lag;

Fig. 7 is a fragmentary vertical section, similar to Fig. 3, of a modified form of means for securing lagging upon a reel.

Fig. 8 is a further modified form of lagging and means for securing lagging upon a reel, and

Fig. 9 is a fragmentary vertical section taken on the line 9—9 of Fig. 8.

Referring now to the drawings, and particularly to Figs. 1 and 2, one form of lagging embodying the invention is illustrated, for example, in conjunction with a cable reel comprising a pair of spaced heads 10, interconnected by a drum 11 (Fig. 1) for holding a lead covered cable 12, (Figs. 2 and 4) or other heavy material that may be wound thereon. The cable reel itself may be of any suitable construction, although a welded all-metal construction is preferred. In the construction illustrated, the heads each comprise an outer annular rim 14 concentric with the drum 11 and a plurality of corrugated plates of segmental shape welded together to form an annular head plate 15 and welded at its inner and outer peripheries to the drum 11 and outer annular rim 14, respectively.

One form of lagging embodying the invention comprises a plurality of segmental shaped lags 16 (Figs. 2 and 4) of uniform size and construction and sufficient in number so that when placed side by side on the rims 14 and across the width of the reel, as shown in Figs. 1 and 2, a covering or enclosure is provided for the cable storage space of the reel except for a peripheral space which is less than the covering provided by one of the lags 16 which space is closed by a filler or sealing lag 17, which will be described presently.

Each lag 16 preferably comprises a plurality of integral channel-like formations 18 formed from a single sheet of metal with radially extending relatively short arms 19 at each end. Welded at their inner sides to the edges of the channel-like formations 18 at each side thereof is a reinforcing side wall member 21 which extends from one end to the other of the lag to tie the channel formations 18 and end arms 19 together to form a rigid structure. The wall members 21 extend from the outer peripheral edges of the channel web walls inwardly to a predetermined distance from the outer surfaces of walls 22 (Figs. 2 and 3) interconnecting the channel formations 18 for

30

35

40

45

50

55

a purpose which will be referred to presently. The lag 16 is further strengthened intermediate the side walls 21 by a member 23 which is T-shaped in cross-section, the member being welded to the spaced inner surfaces of the walls 22 and also to end walls 24 (Fig. 5) from which the end arms 19 extend radially. Each end of the lag is further strengthened by an inverted irregular shaped member 25 (Fig. 5) U-shaped in cross-section and arranged opposite the member 23 and welded along all of its edges to the surfaces of the adjacent channel formation 18 and the end arm 19 and the end wall 24 extending between the arm and the channel formation. Struck out from the walls 22 interconnecting the channel formations 18 of the lag 16 adjacent the side walls 21 and arranged to extend over the inner edges of the head rims 14 are tabs 26 which serve to effectively prevent substantial longitudinal movement of the lags on the reel.

One embodiment of the improved means for securing the lagging of the above described type to the reel head rims 14 comprises the following. At each side of the lag 16 the opposite side edges 25 of the side arms of the channel formations 18 and the end arms 19 are slotted, as indicated at 28 (Fig. 3), in the space provided between the outer surfaces of the walls 22 and 24 interconnecting each of the channel formations and the end arms and the inner edges of the side walls 21 for the reception of steel retaining tapes or bands 29 which encircle the rims 14 and tie the lags under tension to the reel heads 10. The dimensions of the slots 28 relative to that of the bands 29 are such that the bands may be freely entered into slots. To insure that the bands 29 will not accidentally move out of the slots 28 during movement and transportation of the reel, each reel head 10 has bolted to the inner periphery of its rim 14 at substantially opposite points a pair of L-shaped tape retaining clips 30. The clips are formed with an arm 31 which extends over the outer edge of head rim 14 and the band 29, thus preventing outward movement of the band from its lag retaining position in the slots 28.

To secure the lags 16 to the head rims 14 the reel is preferably mounted on a suitable device whereby it may be freely rotated during the securing of the lags. The first lag 16 is fixed to the pair of head rims 14 by aligning the apertures provided at opposite sides of the lag, for the reception of the bolts used to retain the clips 30 in band retaining position, with the corresponding apertures in the head rims, also provided for the clip holding bolts. It is to be understood that each of the lags 16 is provided with similar apertures although in the completed enclosure for the reel only two substantially opposite lags have the band retaining clips 30 attached thereto. Thereafter bolts are entered in the aligned apertures and nuts are threaded onto the inner ends of the bolts. If found necessary additional clips 30 may be employed.

A temporary tie member or band may be suitably attached to the first secured lag 16 intermediate the head rims 14 drawn over the outer periphery thereof and sufficient tension maintained in the band to hold the following lags as they are placed in abutting relation around the peripheries of the head rims 14 as the reel is rotated. When a requisite member of lags 16 has been placed in position to completely enclose the cable storage space of the reel, except for the peripheral space to be filled in by the sealing lag 17 the temporary band is drawn up tightly and

suitably retained. The peripheral rim surfaces to be engaged by the lag 17 serves to provide suitable spaces for sealing the ends of the retaining bands 29. The permanent tie member or band 29 is then inserted in the series of slots 28 provided in each of the lags 16 at each side thereof and when the bands have been completely extended around the two series of slots they are drawn up tightly under a desired tension and a sealing or tying member 32 (Fig. 4) is attached to the overlapping ends of each band extending across the peripheral rim surfaces to be engaged by the opposite ends of the lag 17 to maintain the applied tension, thus effectively securing the lags 16 to the reel. Thereafter the temporary tie member 15 is released and removed from the reel.

The sealing lag 17 (Figs. 4 and 6), previously mentioned, which is used to fill in the space not occupied by the lags 16 comprises a single channel formation 35 reinforced and strengthened in a 20 manner similar to the lags 16 and provided with slots 36 at each side for the entrance of the retaining bands 29, the slots being similar to the slots 28 of the lags 16 except that the slots 36 at one side, the side thereof which is first entered 25 in the space between the first and last of the lags 16 mounted on the reel are twice as deep as the slots 36 at the opposite side and the slots 28 of the lags 16. To complete the enclosing of the reel the sealing lag 17 is slid into position in the 30 space left between the first and last lags 16, previously mounted on the reel, the side of the lag 17 having the deepest slots 36 being first moved into position between the lags 16 across the head rims 14 from right to left as viewed in Fig. 2 and the 35 tensioned retaining band 29 along with the sealing member 32 at the left side of the head rim is raised off the rim sufficiently to permit the band to be inserted in the deep slots 36 and the lag is then shoved over sufficiently to clear the band 29 at the right side of the head rim. Thereafter, the 40 lag 17 is moved back and the latter band 29 along with the sealing member 32 is raised off the rim sufficiently to permit it to be entered in the short slots 36 of the lag. To lock the lag 17 in position to prevent longitudinal movement thereof on the 45 reel it is bolted at one side thereof as indicated by bolt apertures 37 (Fig. 6) to the head rim. The band retaining clips 30 are then bolted to each head rim 14 at diametrically opposite sides which 50 completes the enclosing of the reel.

In Fig. 7 there is shown a modified form of the means shown in detail in Fig. 3 for securing the lagging upon the reel wherein each wall 40 interconnecting spaced channel formations 41 of each lag 42 are formed at their outer sides 55 with integral upturned short lips 43 extending across the space between side arms of each channel formation. The lips 43 are in line with opposite side wall members 44 of the lags, the inner edges of the side wall members being spaced a 60 predetermined distance from the upper edges of the lips 43. Side edges of the side arms of each channel formation 41 are slotted, as indicated at 45, the slot extending between the outer surface of the wall 40 and the inner edge of the side wall member 44 and for a suitable distance inwardly. Thus a steel retaining tape or band 46 may be entered through the continuous slot provided between the opposed edges of the side wall member 44 and the upturned lips 43 and dropped 70 onto the upper surfaces of the walls 40 and behind the inner surfaces of the lips 43. After the bands 46 are in position behind the series of lips 43 at each side of the reel they are drawn up tightly under a desired tension and their ends 75

sealed or tied in a manner similar to that described hereinbefore in connection with the other embodiment of securing means. It will be apparent that in the construction shown in Fig. 7 the bands 46 will be effectively prevented from moving out of the slots 45 without the use of clips similar to the clips 30 of Fig. 3 or other retaining members by means of the lips 43 formed integral with the lags.

10 Figs. 8 and 9 illustrate a still further embodiment of lagging and means for securing the lagging upon a reel, the lagging comprising a series of lags 50 and a filler lag 51 which may follow the general formation and construction of the 15 lags 16 and 17 shown in Figs. 1 to 6, inclusive. Outer peripheral curved web walls 52 of each channel formation 53 of the lag 50 are formed with a pair of depressions or embossments 54 which extend across the entire width of the walls 20 52 and are spaced a suitable distance from each side of the lag, the series of embossments at each side of the lag being aligned. The filler lag 51 is also formed with embossments 57 in its peripheral curved web wall 58 of its single channel 25 formation 59, which are aligned with the embossments 54 of the lag 50. In each space between adjacent channel formations 53 and 59 of the lags 50 and 51 and centered with the embossments 54 and 57 is fitted a formed up and 30 welded box-like member 60 having its outer surface in the plane of the outer surface of the embossments 54 and 57 and retained in position by welding to the side arms of the channel formations 53. At opposite ends of each of the 35 lags 50 and 51 between radially extending short arms 61 and the adjacent channel formations of the lags and aligned with the embossments 54 and 57 thereof are fitted formed up and welded box-like members 62 which are retained in position by welding. Outer end walls 63 of the box-like members 62 are formed to abut and lie in the plane of the short end arms 61 of the lags 50 and 51 in order that no appreciable space will occur between the ends of the lags.

45 In securing the lags 50 and 51 to the reel head rims 14 the method described in connection with the structure shown in Figs. 1 to 6, inclusive, may be generally employed except that a steel retaining tape or band 64 is entered in each series of 50 aligned embossments 54 and 57 extending around the reel, the bands being drawn up tightly under a desired tension and a sealing or tying member 65 attached to the overlapping ends of each band which effectively secures the lagging to 55 the reel. It will be apparent that the box-like members 60 and 62 not only serve to support the bands 64 across the spaces between the embossed channel formations 53 and 59 and the short arms 61, thus providing a continuous supporting surface around the periphery of the lagged reel, but also serve as strengthening or 60 reinforcing means for the lags. In the lag construction of Figs. 8 and 9 employing the box-like members 62 the use of a U-shaped member 25, 65 as in Figs. 1 to 7, inclusive, is not necessary since the members 62 serve as strengthening members for the ends of the lags. The embossments 54 and 57 not only serve to prevent the securing bands 64 from shifting laterally on the periphery 70 of the lagged reel, but also permit the bands to lie slightly within the periphery of the lagged reel, thereby protecting them from damage during rolling of the filled reel.

75 For preventing substantial longitudinal movement of the lags 50 on the reel, angle members

68 are welded to walls 69 interconnecting the channel formations 53, the angle members being fixed adjacent reinforcing side wall members 70 and arranged to extend over the inner edges of the reel head rims 14.

The reel lagging and securing means therefor in the several embodiments constructed and arranged as above described provides a simple rigid structure having a low weight consistent with its strength and offering a maximum resistance 10 against impact stresses encountered in normal service of a reel and the several embodiments of securing means permits the lags to be readily and effectively secured to the reel and easily removed therefrom.

15 It is to be understood that the invention is not limited to the specific embodiments described, but is restricted only by the scope of the appended claims.

What is claimed is:

1. A lag for a reel having spaced heads comprising a member having a plurality of channel-like formations having opposite side portions bearing directly upon and extending across the peripheries of the heads, and opposite side wall members united to and interconnecting the side edges of the formations at the outer peripheral edges of the heads.

2. A lag for a reel having spaced heads each with a peripheral rim comprising a member having a plurality of integral channel-like formations having inner spaced peripheral portions bearing directly upon and extending across the peripheries of the rims, and opposite side wall members secured to and interconnecting the side edges of the formations at the outer peripheral edges of the rims.

3. A lag for a reel having spaced heads each with a peripheral rim comprising a member having a plurality of channel-like formations joined by inner peripheral portions bearing directly upon and extending across the peripheries of the rims, a radially extending arm at each end of the member, and opposite side wall members united to and interconnecting the side edges of the formations and the end arms at the outer peripheral edges of the rims.

4. A lag for a reel having spaced heads each with a peripheral rim comprising a member having a plurality of integral channel-like formations joined by inner peripheral portions bearing directly upon and extending across the peripheries of the rims, an arm at each end of the member spaced from the end formation and extending radially from end portions bearing upon the rims, opposite side wall members united to and interconnecting the side edges of the formations and the end arms at the outer peripheral edges of the rims, and a reinforcing element at each end of the channel-like member united to the end arm, end formation and end portion.

5. A lag for a reel having spaced heads each with a peripheral rim comprising a member having a plurality of integral channel-like formations joined by inner peripheral portions adapted to bear upon the rims, an arm at each end of the member extending radially from end portions adapted to bear upon the rims, opposite side wall members united to and interconnecting the side edges of the formations and the end arms, and a reinforcing element arranged between the rims and united to inner surfaces of said portions.

6. A lag for a reel having spaced heads each with a peripheral rim comprising a member hav-

- ing a plurality of integral channel-like formations joined by inner peripheral portions bearing directly upon and extending across the peripheries of the rims, elements carried by and 5 projecting inwardly from said portions and disposed adjacent the inner sides of said rims for preventing substantial longitudinal movement of the lag on the reel, and opposite side wall members united to and interconnecting the side edges 10 of the formations at the outer peripheral edges of the rims.
7. A lag for a reel having spaced heads each with a peripheral rim comprising a member having a plurality of channel-like formations joined 15 by inner peripheral portions adapted to bear upon the rims, an arm at each end of the member extending radially from end portions adapted to bear upon the rims, opposite side wall members welded to and interconnecting the side edges of 20 the formations and end arms, a reinforcing element of U-shaped cross-section at each end of the member welded to the end arm, end formation and end portion, a reinforcing element arranged between the rims welded to and inter- 25 connecting the inner surfaces of said portions, and elements carried by and projecting inwardly from said portions joining the formations and disposed adjacent the inner sides of said rims for preventing substantial longitudinal movement of 30 the lag on the reel.
8. Lagging for a reel comprising a plurality of lags extending around and bearing upon the periphery of the reel, said lags being slotted at their sides to receive retaining members, and retaining members entered in said slots and encircling the reel for securing the lagging against the periphery of the reel.
9. Lagging for a reel having spaced heads each with peripheral rim comprising a plurality of lags for encircling, spanning and bearing upon 40 the rims, each of said lags provided with slots in their sides adjacent the peripheral surfaces of the rims for the reception of retaining members, and retaining members entered in said slots encircling the rims and applied under tension for 45 securing the lagging upon the reel.
10. Lagging for a reel having spaced heads each with a peripheral rim comprising a plurality of channel-like members for encircling and spanning the rims, inner peripheral surfaces of 50 said members bearing upon the rims, each of said lags provided with slots in their opposite side edges adjacent their inner peripheral surfaces for the reception of retaining members, and retaining members entered in said slots encircling the rims and applied under tension for securing the lagging upon the reel.
11. Lagging for a reel having spaced heads each with a peripheral rim comprising a plurality of lags for encircling and spanning the rims, 55 each of said lags having a plurality of integral channel-like formations bearing at their inner peripheries upon the rims, the opposite side edges of said formations adjacent their inner peripheries being slotted for the reception of retaining bands, and retaining bands entered in said slots encircling the rims and applied under tension for securing the lagging upon the reel.
12. Lagging for a reel having spaced heads 60 each with a peripheral rim comprising a plurality of members each having a plurality of channel-like formations joined by inner peripheral portions bearing upon the rims, the opposite side edges of said formations adjacent the outer surfaces of said portions being slotted for the recep-

tion of retaining members, side wall members united to opposite side edges of the formations and extending from the outer peripheral surfaces of the formations to the outer edges of said slots, and retaining members entered in said slots encircling the rims and applied under tension for securing the lagging upon the reel. 5

13. Lagging for a reel having spaced heads each with a peripheral rim comprising a plurality of lags for encircling, spanning and bearing upon the rims, each of said lags provided with slots in their sides adjacent the peripheral surfaces of the rims for the reception of flexible retaining members, flexible retaining members entered in said slots encircling the rims and applied under tension for securing the lagging upon the reel, and means secured to the rims at a plurality of points and extending past the outer edges of the retaining members for preventing movement of the members out of said slots. 20

14. Lagging for a reel having spaced heads each with a peripheral rim comprising a plurality of lags for encircling and spanning the rims, each of said lags having a plurality of integral channel-like formations bearing at their inner 25 peripheries upon the rims, the opposite side edges of said formations adjacent the inner peripheries thereof being slotted for the reception of retaining bands, retaining bands entered in said slots encircling the rims and applied under ten- 30 sion for securing the lagging upon the reel, and means secured to the inner peripheries of the rims at a plurality of points each disposed between a pair of slotted side edges of said formations, said means extending past the outer edges 35 of the retaining bands for preventing movement of the bands out of said slots.

15. Lagging for a reel having spaced heads each with a peripheral rim comprising a plurality of lags extending around and bearing upon the 40 rims, said lags provided with slots at their sides for the reception of retaining members, the outer sides of said slots having a wall extending angularly from the bottom wall of the slot to a pre-determined distance from the upper wall thereof 45 to provide an opening for the entering of retaining members, and retaining members entered in said slots and behind said angularly extending walls, encircling the rims and applied under tension against the bottom walls of said slots for 50 securing the lagging upon the reel.

16. Lagging for a reel having spaced heads each with a peripheral rim comprising a plurality of lags for spanning and bearing upon the rims, the lags being only sufficient in number to partially encircle the rims thereby providing an open space to be filled in, each of said lags provided with slots in their sides adjacent the peripheral surfaces of the rims for the reception of retaining members, retaining members entered in said slots encircling the rims and applied under tension for securing the lagging upon the reel, the ends of the tensioned members being located in spaces at each side of the reel, means for tying the ends of the tensioned members in said spaces, a lag for 60 filling said open space provided with slots in its opposite sides adjacent the peripheral surfaces of the rims for the reception of the tensioned member, the slots in one side of the filler lag being longer than those in the opposite side thereof 65 so that the tensioned member at one side may be first entered in the longer slots by a longitudinal movement of the lag in one direction and there- 70 after moved in the opposite direction to enter the opposite tensioned member in the shorter 75

slots, and means for securing said latter lag in its last position.

17. Lagging for a reel having spaced heads each with a peripheral rim comprising a plurality of members, each having a plurality of channel-like formations joined by inner peripheral portions bearing directly upon and extending across the peripheries of the rims, opposite side wall members secured to and interconnecting the side edges of the formations at the outer peripheral edges of the rims, and banding means encircling the reel for securing the lagging to the spaced heads.

18. Lagging for a reel having spaced heads comprising a plurality of members each having a plurality of channel-like formations joined by

inner peripheral portions bearing upon the heads, said members encircling the heads, peripheral web walls of said members being embossed adjacent their end portions for receiving and retaining members for holding the lags in position 5 upon the heads, elements arranged in the spaces between and fixed to adjacent channel formations and aligned with the embossed portions of the outer peripheral web walls effective for supporting the retaining members, and retaining 10 members supported in the embossed portions of said web walls and upon said elements, encircling the heads and applied under tension for securing the lagging upon the reel.

ARTHUR A. BUREAU. 15
